ARTIFICIAL HAND

Raymond B. Trautman, Minneapolis, Minn.

Application January 24, 1930. Serial No. 423,049

11 Claims. (Cl. 3—12)

My invention relates to artificial hands and particularly to hands having fingers and thumbs articulated thereon and adapted conjointly to open and close to grasp and hold objects in simulation of the human hand.

An object of the invention resides in providing separate means for operating the fingers and thumb and in individually locking the thumb and fingers when in closed position.

10 A still further object resides in effecting the locking of the thumb and fingers through members fixedly attached to said thumb and fingers.

Another object of the invention resides in providing an arm for controlling the movement of the thumb and another arm for controlling the movement of the fingers.

20 Another object of the invention resides in providing a pivoted finger frame constructed with an actuating lever having a cam track for cooperation with its respective arm and in similarly providing said thumb with a lever having a track for cooperation with the other arm.

A still further object of the invention resides in the provision for locking said fingers and thumb against movement by means of said arms and levers when said arms are in finger and thumb closing position.

25 An object of the invention resides in constructing the lever for the finger frame with a cam surface and in providing the corresponding arm with a roller for engagement with said cam surface.

30 An additional object of the invention is, generally, to minimize the number of parts and to eliminate play and this, specifically, by employing a single spring to impart an opening swing to the fingers, under the control of the finger frame cam in cooperation with its corresponding lever and, further, to close said fingers by throwing 35 said lever in a direction causing it to coat with said cam and thereby swing the finger frame in finger closing direction.

Another object of the invention resides in providing a draw cord having a connection with said arms for shifting both thereof to move the thumb and the fingers conjointly.

40 A feature of the invention resides in connecting the draw cord to both arms, the connection with one arm being through a sheave mounted thereon so as to produce a shifting connection and thus allow for compensation between the operating means for the thumb and fingers.

45 Other objects reside in the novel combination and arrangement of parts, and in the details of

construction hereinafter illustrated and/or described.

In the drawings:

Fig. 1 is a plan view of an artificial hand illustrating an embodiment of my invention, the removable cover being detached to disclose the interior construction, the fingers being shown in closed position.

Fig. 2 is a view partly in elevation and partly in section of the hand shown in Fig. 1.

Fig. 3 is a view similar to Fig. 1 showing the fingers in open position.

Fig. 4 is a view similar to Fig. 2 showing the fingers in open position.

The hand proper comprises a body member 10 of wood or other suitable material simulating the metacarpus of the human hand. This body member 10 is hollowed out to form a chamber 11 therein for the reception of the operating mechanism of the device. At the wrist of the body member 10 is provided a threaded shank 33 by means of which the hand may be attached to the ordinary stump socket in the customary manner. In the forward portion of the body member 10 is formed an opening 12 which communicates with the chamber 11, and at one side and toward the lower part of the body member is formed a slot 13 which similarly communicates with the chamber 11.

The thumb of the hand, designated at 14, is constructed solid, preferably from the same material as the body member 10 and is formed with a tongue 15 which is received within the slot 13 previously referred to. This thumb is articulated on the body member 10 in a manner closely simulating the movement of the human thumb, a pintle 16 in the member 10 passing through the tongue 15 of thumb 14.

In forming the fingers 17, 18, 19 and 20 of the hand, I employ four spaced rods 21, 22, 23 and 24, all of which are attached to a bar 25 common thereto, the rods and bar constituting a finger frame. Mounted upon each of said rods is a finger body 65 of a composition of rubber and cork or other suitable material and enveloping each finger body is a covering 66 of leather or the like. If desired, however, the fingers may be constructed of wood or other solid material, in which case the rods need merely extend a short distance into the butts of the finger bodies.

The bar 25 to which the fingers of the hand are attached serves as a shaft for pivoting the entire finger structure for movement in a direction toward and from the thumb 14. This bar is formed intermediate the ends thereof with two

reduced annular portions 27 which are journaled in two bearings 28 and 29. These bearings are attached to a plate 30 by means of screws 31, said plate constituting a supporting frame for the finger structure and for some of the operating parts of the hand. This plate 30 together with the bar 25 and appurtenant actuating parts extend into the opening 12 of the body member 10, the fingers extending from the body 10 in a natural manner, the actuating parts being disposed to permit of the operation thereof by mechanism contained within the chamber 11 of said body 10 of the hand. The screws 31, extending through the plate 30 and into the body member 10 of the hand, hold the bearings 28 and 29 and the said plate 30 in place. This plate is further secured to the hand proper through an other screw 32 threaded into the body member 10.

Mechanism for operating the thumb 14 includes a lever 34 formed with a head 60 attached to the tongue 15 by screws 35 or other suitable fastening means. A pintle 36 inserted into the body member 10 immediately below the plate 30 and passing through an enlargement 11^a of the chamber 11 thereof provides a pivotal mounting for a swinging arm 37. Near the free end of this arm 37 is a lug 38 which projects into and rides along a slot 39 formed longitudinally of the lever 34, said lug serving to depress or elevate the lever 34, according to the direction of movement of the arm 37, and thereby cause the thumb 14 to swing from its closed position as shown in Fig. 2 into its open position as shown in Fig. 4 or vice versa. The arm 37 is normally held in the position shown in Figs. 2 and 4 by means of a spiral spring 40 encircling the pintle 36. One end of this spring is lodged in an opening 41 in the arm 37 and the other end thereof is hooked over the edge of the plate 30. This spring 40 is arranged to move the arm 37 toward the position shown in Fig. 2 thereby yieldingly forcing the thumb 14 into closed position. It is to be noted that due to the disposition and arrangement of parts, when the lug 38 is in the position shown in Fig. 2, movement of the thumb 14 from its closed position as by force applied to the thumb, is precluded, thereby effecting a lock for holding the thumb closed. However, upon a swinging movement of the arm 37 in a counter-clockwise direction as viewed in Figs. 2 and 4 and against the action of spring 40, the thumb may be readily swung into open position. The closing of the thumb is accomplished by releasing the arm 37, the return movement of which is effected through the spring 40.

In mechanism for actuating the fingers 17, 18, 19 and 20, I employ a bell-crank 43, which is pivoted on a screw 44 screwed into the plate 30 and into the body member 10. This bell-crank includes an arm 45 extending toward the bar 25 and another arm 46 extending substantially parallel with said bar and at right angles to the arm 45. Said arm 45, forked at its free end, receives a small roller 48 which is journaled therein on a pin 49. This roller 48 cooperates with an elongated cam 50 secured to, but offset from the bar 25, said cam forming a short lever through which the finger frame is rocked in finger closing direction and through which the reverse movement of said frame is regulated. A cam surface 51 on cam 50 contacts with the roller 48, said surface extending generally in the direction of bar 25 and spiralling slightly. A spring 52, stretched over the bar 25 and frame plate 30, has one end thereof caught on the finger rod 22 and the other end thereof secured to the arm 46 of

said bell crank 43 by means of a screw 53. This spring 52 tilts the finger frame in finger opening direction, the cam 50 permitting in its cooperation with roller 48 upon a swinging movement of the arm 45 in a direction toward the thumb 14. Said spring 52 further effects a closing movement of the fingers by actuating the bell-crank 43 to swing the arm 45 in a direction away from the thumb and cause the roller 48, through the cam 50, to swing the finger frame. Two stops 54 and 55 limit the movement of the arm 45, so as to terminate the movement of the fingers, when in fully open position and fully closed position.

The thumb and fingers of the hand are operated through a draw cord 56 secured at one end 57 to the lower end 58 of the arm 37. This draw cord is looped about a sheave 59 journaled on a pintle 60 mounted in a forked bracket 61 formed on the arm 46 of the bell crank 43. The draw cord 56 extends up through an opening 56^a in the body member 10 of the hand and runs up along the arm of the user where it may be actuated in the ordinary manner as by being looped about the shoulder.

The body 10 of the hand may include a cover 62 capping the chamber 11 and encasing the plate 30 and mechanism attached thereto. Upon removal of this cover all of the operating parts of the hand become accessible.

In the use of the hand, the tensioning of the draw cord causes the opening of the thumb and fingers. As this cord is tensioned, it exerts a backward pull upon the lever 37 and upon the arm 46, the sheave 59 on said arm 46 turning under the cord as need be in a compensating manner. Thus, the backward movement of the lever 37 and arm 46 causes the opening of the fingers and thumb conjointly. Arm 45 engages the stop 55 when the fingers and thumb have reached fully open position. Upon releasing the cord 56, the spring 52 and the spring 40 draw the fingers and thumb back into normally closed position causing the same to grip and hold an object grasped by the hand. When the arms 37 and 45 reach closing position, as shown in Figs. 1 and 2, or somewhat nearly so, the lug 38 on the arm 37 is so disposed within the slot 39 of the lever 34 as to prevent the opening of the thumb 14 and to lock the same closed and, at the same time, the roller 48 is disposed in relation to the cam surface 51 of the cam 50 so as to hold the fingers 17, 18, 19 and 20 closed and locked. This permits of using the hand for carrying baggage or performing other work where it is desirable to have a positive grip on the articles to prevent accidental opening of the hand and the consequent releasing of the objects held.

The advantages of my hand are apparent. An extremely simple and positive device is provided, whereby articles may be conveniently and firmly grasped and held and manipulated in any desired manner. The fingers and thumb are locked through members fixed relative thereto, thereby eliminating lost motion and reducing the number of elements through which the strain is transmitted. The mechanism is so designed as to be readily confined within a space such as permits of the construction of the hand in simulation of the human hand. Both the thumb and fingers are conjointly operated through a single draw cord and these members, when in closed position, are locked so as to prevent the unintentional opening of the hand. A dual functioning spring taking up play between parts, normally closes the finger frame, through the bell-crank 43 and cam 50.

50, and opens said frame, upon the tensioning of cord 56, under control of the coacting cam 50 and roller 48.

Changes in the specific form of my invention, 5 as herein disclosed, may be made within the scope of what is claimed without departing from the spirit of my invention.

Having described my invention, what I claim as new and desire to protect by Letters Patent is:

10 1. An artificial hand comprising a supporting structure, a finger pivoted to said supporting structure, an arm also pivoted thereto and movable in a plane containing the axis of the finger pivot, a lever on said finger forming an elongated track, and means carried by said arm for engagement with said track to control the movement of said finger.

20 2. An artificial hand comprising a supporting structure, a finger pivoted to said supporting structure, a bell-crank pivoted to said structure and movable in the plane of the axis of the finger pivot, a lever on said finger presenting an elongated track, one of the arms of said bell-crank serving to engage said track to control the movement of said finger, and a spring connected to said finger and to the other arm of said bell-crank and operating to swing both thereof.

30 3. In an artificial hand, a body portion, a finger articulated thereon, a movable member mounted on said body portion and operating to swing the finger one way when moved in one direction and to control the retraction of said finger when moved in the opposite direction, a spring acting to move said member in said first direction, means operable against the action of said spring to retract said member, said spring serving further to retract said finger under the control of and during such retraction of said member.

40 4. An artificial hand comprising a supporting structure, a finger pivoted to said supporting structure, a lever attached to said finger and extending in the direction of the axis of the pivot for said finger, an arm pivoted to said supporting structure for engagement with said lever at various localities along the length thereof, said arm being movable toward and from said lever to limit the position of the finger, means for moving said arm in one direction and resilient means for moving said arm in the other direction.

50 5. An artificial hand comprising a supporting structure, a finger pivoted to said supporting structure, an arm pivoted to said structure, a lever on said finger presenting an elongated track, said arm engaging said lever and movable along said track to control the movement of said finger and a spring connected to said finger and to said arm.

60 6. An artificial hand comprising a supporting structure, a finger pivoted to said supporting structure, a lever on said finger, an arm pivoted to said structure and adapted to engage said lever to control the movement of said finger and a spring connected to said finger and to said arm.

7. An artificial hand comprising a supporting structure, a finger pivoted to said supporting structure, a lever on said finger presenting an elongated track, an arm pivoted to said supporting structure and having a portion movable along said track, and a spring connected to said finger and to said arm for urging said arm against said track, said spring having a greater leverage upon said arm than on said finger to cause the arm to move along said track.

80 8. An artificial hand comprising a supporting structure, a finger pivoted to said supporting structure, an arm pivoted to said supporting structure, means disposed between said arm and finger for imparting movement from one thereof to the other, said means including two contacting parts, and a spring eccentrically connected to said finger and arm, and operating to move said arm in one direction and to hold said parts in contact during the movement of the arm in such direction, and means for moving the arm.

90 9. An artificial hand comprising a supporting structure, a finger pivoted to said supporting structure, an arm pivoted to said supporting structure, means disposed between said arm and finger for imparting movement from one thereof to the other, said means including two contacting parts, and a spring eccentrically connected to said finger and arm, the eccentricity of said spring relative to the arm being greater than its eccentricity with respect to the finger to cause the arm to move in one direction, said spring holding the parts in contact during such movement and means for moving the arm.

100 10. In an artificial hand, a body portion, a finger supporting bar axially rockable on said body portion, fingers mounted on said bar, a lever on said bar presenting an elongated cam surface extending generally in the direction of the axis of the bar, an arm pivoted on said body portion 110 for endwise abutting contact with said lever along said cam surface, and means for swinging the arm, said arm through its cooperation with said lever, serving upon movement in one direction to close the fingers and upon movement in the reverse direction to control the opening of said fingers.

110 11. In an artificial hand, a body portion, a finger supporting bar axially rockable on said body portion, fingers mounted on said bar, cooperating cam elements, one mounted on said bar and one on said body portion, the latter being movably mounted, means for moving said latter element, said elements being adapted to contact with each other along a line extending in the general direction of the axis of said bar and serving, upon movement of said second element in one direction to close said fingers and upon movement of said second element in the reverse direction to control the opening of said fingers.
